UNITED STATES PATENT OFFICE.

THOMAS DONOHOE, OF EDGEWOOD, PENNSYLVANIA.

COAL-MINING MACHINE.

1,387,886.

Specification of Letters Patent. Patented Aug. 16, 1921.

Application filed October 18, 1915. Serial No. 56,372.

To all whom it may concern:

Be it known that I, THOMAS DONOHOE, a citizen of the United States, and resident of Edgewood, in the county of Allegheny and State of Pennsylvania, have invented certain new and useful Improvements in Coal-Mining Machines, of which the following is a specification.

The object of this invention is to provide a machine of improved construction for undercutting and for removing the overhanging or undercut breast of coal as the undercutting proceeds, as distinguished from the present method of undercutting and removing the machine before dropping and loading the coal.

The invention is embodied in a machine wherein a vertically shallow platform supports the undercutting means and upon which the undercut coal is adapted to be dropped either while the undercutting means is operating or at a standstill, as may be preferred, together with conveyer means for receiving the coal from the platform and delivering it directly to pit cars or wagons for removal from the mine. Practically the entire operation of mining is thus performed by one and the same machine, with such complete operation proceeding as rapidly as the coal is undercut, thereby eliminating many of the operating steps heretofore necessary and correspondingly decreasing the expense of and expediting the work.

The invention includes a coal delivering conveyer of improved construction for receiving coal dropped on the undercut-entering platform; also mechanism of improved construction carried by the platform for moving the dropped coal to position to be taken up by said conveyer. The delivery conveyer is preferably arranged at an upward incline and with the point of delivery located in the highest portion thereof and at sufficient elevation to drop the coal into a pit car or wagon located therebeneath.

In the accompanying drawings, Figure 1 is a side elevation of the improved machine shown in operative position, and Fig. 2 is a view in top plan of the same. Fig. 3 is a longitudinal section of the machine taken on line 3—3 of Fig. 2. Fig. 4 is a cross-section of the platform-forming forward portion of the machine taken on line 4—4 of Fig. 2. Figs. 5 and 6 are sectional views on a larger scale illustrating the conveyer

bars and bar actuating mechanism for moving the coal on the platform in position to be taken up by the delivery conveyer. Fig. 7 is a detail view, illustrating the vertical adjustment for the ground wheels.

Referring to the drawings, 2 designates the horizontal platform-forming forward portion of the portable frame which is relatively shallow vertically in order that it may freely enter an undercut A in the breast of coal B. The platform may be constructed of top and bottom horizontal plates 3 and 4, respectively, which are separated by and secured to the girder-like spacing bars 5. The rear portion of the platform portion 2 is defined by the relatively heavy girder 6 which extends transversely of the frame from side to side and depending therefrom and forming the transverse shoe-like support 7. The latter is flanged rearwardly at 8 and secured thereto is the horizontal part 9 of the rearward portion of the frame, the latter having an upward offset at 10 whereby the rearmost portion 11 of the frame is spaced above the mine floor C, Fig. 3. Frame part 11 is provided at its rear with the floor engaging wheels 12, and the mountings for these wheels are vertically adjustable as indicated at 13. By means of this adjustment the angle of undercut A is determined, the machine frame being adapted to rock on shoe 7 upon adjusting wheels 12, thereby raising or depressing the forward portion of the platform in accordance with the desired angle of the undercut.

The forward edge of platform 2 provides a guideway for the endless undercutting chain 15, the chain passing around suitable idlers 16 at the front and side of the platform and rearwardly therefrom around the chain-driving wheel 17, the latter being geared to an electric motor 18 supported by the frame part 11. This motor is also geared at 19 to the axle 12' of floor wheels 12, whereby the machine is advanced as the undercutting proceeds. Wheels 12 are suitably ribbed or roughened to obtain the necessary traction, the forward portion of the machine sliding on the under face of platform 2 and on shoe 7, as will be understood.

The portion of platform 2 which defines the path of the chain cutter may be of any preferred shape or outline. As here shown, it is substantially V-shaped with its apex or angle at the longitudinal center of the machine, whereby a cut of corresponding form

is had, the tendency of which is to hold the machine in a straight-ahead course. The chain cutter 15 is of the type usually employed for undercutting, and for which no 5 novelty is claimed.

The top plate 3 of platform 2 is slotted at 20, the slots being disposed in the direction of movement of the frame and adapted to project through each slot is a toothed bar 21, the free forward end of which slides on bottom plate 4 between the spacing bars 5. The rear ends of bars 21 are secured to cranks 22 of a shaft 23, the latter journaled in the several spacing bars 5 and extending 15 from side to side of the platform between plates 3 and 4. Crank shaft 23 may be connected by the worm gearing 24 with the rearwardly extending shaft 25, the latter being geared at 26 to shaft 27 of electric motor 20 28 mounted on the rearward portion 11 of the frame.

By this arrangement each bar 21 has its rear portion traveling in a circular path, the front end reciprocating back and forth 25 on plate 4, shaft 23 moving clock-wise in Fig. 5. As a result the toothed face of each bar is housed at one time and at another time is exposed, the exposed portion of 30 travel being in a direction to raise lumps of coal and carry them rearwardly to a depositing point, whereupon the bar passes below the top plane of plate 3 and moves forwardly while thus housed. This provides an intermittent feed of the coal rearwardly, 35 the slow speed tending to prevent breaking up of coal lumps and at the same time carrying the remaining portions of the coal rearwardly into the conveyer.

Various means, automatic or otherwise, 40 may be employed for receiving and removing the coal from platform 2. In the present embodiment, at the rear of platform 2 is an upwardly inclined conveyer for receiving the coal from said platform and for delivering it to cars or wagons positioned at the rear of the machine. As here embodied, the 45 conveyer trough, way or channel is of triangular form with one leg 30 thereof paralleling the rear side of platform 2 and with 50 the other legs 31 and 32 inclined upwardly from the ends of leg 30 and converging at the highest point 33 where the trough is open as shown for discharging the coal into a pit car 34 positioned beneath the elevated rear end of the conveyer frame, said 55 elevated portion being supported by uprights 35 rising from frame part 11.

The inner side of each leg of the conveyer trough is formed of a channeled bar 36 in 60 which the endless conveyer chain 37 travels and with the conveyer flights 38 shaped to fit the trough as clearly shown in Fig. 5, each flight preferably having an extension 38' which travels over the top edge 65 of bar 36 thereby broadening the transverse

expanses of the flights and at the same time keeping said bar clear of coal accumulation. The forward or lower side of leg 30 of the conveyer trough is formed by the transverse girder 6, and the outer sides of each of the other legs are formed of plates suitably shaped for the purpose, and as illustrated in the drawings the floor or bottom of each leg consists of a plate of requisite form. By this means a substantially triangular open-top 70 trough or way is provided, at each angle of which is a wheel 40 for directing the conveyer chain 37, the wheel at the uppermost rear angle being geared to motor shaft 27 as shown in Fig. 3 whereby the conveyer is 80 propelled by motor 28. By this means both the endless conveyer and the platform conveyer bars 21 may be actuated by the same motor.

In operation, the machine is positioned 85 for making the undercut and after the angle of the latter has been determined by adjusting the floor wheels 12 the chain cutter is set in motion, and by the same motor means the machine is moved forward 90 through the medium of floor wheels 12. As the cutting proceeds, platform 2 is advanced beneath the breast of coal B along with the cutter chain and after an undercut of sufficient depth has been attained, the overhanging coal B may be dropped by blasting, or other suitable means onto platform 2. It will be understood that the mechanism is in operation during the advancing movement of the machine so that while some of the coal 95 may be dropped within leg 30 of the conveyer, coal dropped forwardly on platform 2 will be worked toward and within reach of the latter by the reciprocating bars 21, thus keeping the platform clear and the conveyer 100 loaded. From leg 30 the loaded conveyer moves the coal upwardly over leg 31 and to a point of discharge 33 where it drops off into pit car 34, the empty portion of the conveyer returning for reloading through 105 leg 32.

Various means may be employed for loosening and dropping the undercut coal onto platform 2, the platform serving as a support for the operator or for the mechanism utilized for loosening the coal. As the operation advances, the trackage for the pit cars will be laid so that the latter may be positioned beneath the conveyer discharge, whereby by practically a continuous 115 operation the coal is undercut, dropped, carried backward and loaded into the pit cars. Instead of relying on conveyer bars 21 for moving the coal to within reach of the endless conveyer, after a suitable quantity has 120 been dropped on the platform, the un-dropped portion immediately above the undercut may serve to push the loosened coal toward the conveyer as the platform of the machine advances in the undercut channel. 130

The general arrangement is such that the machine may have a width equal to the width of the room, such width depending to a considerable extent on the strength of the 5 roof, etc., and may range from eight to sixteen feet. The ability to use a machine of this width is brought about by the fact that the coal is not dropped directly upon the conveyer but upon a platform in advance of 10 the conveyer, which platform has a front to rear length sufficient to receive the coal which is dropped, either by use of light blasts or by wedging, and from which platform the coal is moved rearwardly onto the 15 conveyer at a relatively slow speed which will not tend to break up the lumps. Consequently, the conveyer may have its receiving flight equal to the width of the machine and extend transversely of the machine, thus 20 enabling the coal which is fed to the flight to be carried away with sufficient rapidity as to prevent choking of the conveyer system.

This front to rear length of the platform is generally sufficient to permit the cutter 25 chain to cut past the first complete cleavage or face without bringing the transverse conveyer flight in the path of the falling coal, the result being that the coal above the undercut can be brought down by the use of 30 light charges or by a wedging, operations which tend to preserve the lump character of the coal and produce a product of greater value. The toothed bars may then be brought into operation to slowly feed the 35 coal toward the conveyer flight, this operation serving the additional purpose of tending to maintain the machine in its forward position so that the cutting operation may proceed concurrently with this feed movement, the bars thus aiding wheels 12 in advancing the machine. This action is also facilitated by the fact that the advance movement of the machine while the material 40 is on the platform will, through the tendency of the standing face of coal B to push the dropped material rearward as the machine advances, aids the bars in feeding the coal to the transverse flight of the conveyer.

The operation is substantially continuous, 50 the slow advance of the machine being compensated for by the large quantity of coal which is being worked upon, this slow advance affording the operators sufficient time to provide the drill holes or produce the 55 wedging action. Since the machine is of a type which will permit of taking advantage of the natural cleavage in the coal seams, the blasting charges may be light, since there is no necessity for driving the coal rearward 60 into the mining chamber, it being necessary only to sufficiently release the coal and drop it upon the receiving platform.

It will be understood that the structural 65 features of the machine may be variously embodied without departing from the spirit

or scope of the invention, reference to many such details having been omitted herein as they do not vitally concern the principles underlying the construction and operation of the machine.

70

I claim:

1. In a mining machine adapted for use for coal blasting operations, the combination of a portable frame embodying a vertically shallow platform - forming forward portion, undercutting means mounted on and adapted to be advanced by the platform portion into an undercut, the platform adapted to receive coal dropped thereon, a plurality of conveyer bars adapted to reciprocate in said platform and through the upper face thereof and toward and from the rear thereof for moving coal rearwardly on the platform, a shaft journaled in said platform and provided with a plurality of 80 cranks to which the several conveyer bars are operatively connected, shaft rotating means, and means for delivering coal rearwardly from the platform.

2. In a mining machine adapted for use 90 for coal blasting operations, a horizontal vertically shallow coal receiving platform, undercutting means mounted below the upper face of said platform and adapted upon the forward movement of said platform to 95 form an undercut, an endless conveyer movable across and arranged to convey coal from said platform and to carry the same to a point above and in the rear of said platform, and reciprocating means protruding 100 through said platform for moving coal from said undercutting means to said endless conveyer.

3. In a mining machine adapted for use 105 for coal blasting operations, endless undercutting means, a coal supporting frame of vertically shallow depth arranged in the rear of said undercutting means and constructed to project into the undercut and to receive the coal blasted from above the undercut, reciprocating means, mounted substantially throughout the width of said frame, for moving coal thereon to the rear thereof, and an endless conveyer for carrying the coal from said coal moving means 110 to a point above and to the rear of the machine.

4. In a mining machine adapted for use 120 for coal blasting, a coal receiving platform of such height as to be capable of projecting into an undercut, endless undercutting means movable around the forward edge of said platform, an endless conveyer in the rear of said platform, and reciprocating coal moving means between said undercutting means and said endless cover.

5. In a coal mining machine, a frame 130 adapted to enter a horizontal undercut and provided with a central, forward apex, rearwardly inclined edges extending from said

apex and rearwardly extending sides at the ends of said inclined edges, undercutting mechanism mounted on said frame and adapted to operate along the above mentioned apex, edges and sides, said frame having a platform bounded by said apex, edges and sides and provided with a coal-receiving zone and coal removing mecha-

nism adjacent said zone but not intruding thereon.

10

In testimony whereof I affix my signature in presence of two witnesses.
